UNITED STATES PATENT OFFICE.

WILLIAM F. REYNOLDS, OF DAYTON, OHIO.

TUNING-SLIDE FOR CLARINETS.

1,171,647.

Specification of Letters Patent. Patented Feb. 15, 1916.

Application filed May 1, 1915. Serial No. 25,226.

To all whom it may concern:

Be it known that I, WILLIAM F. REYNOLDS, a citizen of the United States, residing at Dayton, in the county of Montgomery and State of Ohio, have invented new and useful Improvements in Tuning-Slides for Clarinets, of which the following is a specification.

The invention relates to tuning slides, 10 and more especially to the class of adjustable tuning barrel joints for clarinets.

The primary object of the invention is the provision of a tuning slide of this character wherein the construction thereof is novel in form and can be conveniently applied to a clarinet so that the latter can be accurately tuned, and in the use thereof enlarged air gaps are avoided, which ordinarily take place when drawing out the barrel joints of the clarinet.

Another object of the invention is the provision of a joint of this character wherein the parts thereof are assembled in a novel manner to permit easy adjustment 25 without liability of separating the joints from the mouth piece or the body of the clarinet.

A further object of the invention is the provision of a joint of this character which 30 is simple in construction, readily and easily adjusted, strong, neat in appearance, reliable and efficient in operation, and inexpensive in manufacture.

With these and other objects in view, the 35 invention consists in the construction, combination and arrangement of parts as will be hereinafter fully described, illustrated in the accompanying drawing, and pointed out in the claim hereunto appended.

40 In the drawing: Figure 1 is a fragmentary side elevation of a clarinet showing the joint constructed in accordance with the invention. Fig. 2 is a vertical longitudinal sectional view thereof. Fig. 3 is a perspective view of the slide tube. Fig. 4 is a perspective view of the stationary tube forming the lining for the barrel joint.

Similar reference characters indicate corresponding parts throughout the several 45 views in the drawing.

Referring to the drawing in detail, A designates a portion of the body of a clarinet, which is of the ordinary well-known construction, B the mouth piece, and C the

tuning slide barrel joint hereinafter fully 55 described.

The barrel joint C comprises a stationary tube 5 preferably made from metal forming a lining for the barrel 6, preferably made from ebonite, thereby eliminating the cracking possibility, the said lining being formed with an enlarged end 7, while the barrel 6 is correspondingly shaped thereto and has its opposite end formed with a socket 8 in which is detachably fitted the body portion 65 of the clarinet.

Within the stationary tube 5 is a slide tube 9 formed with an enlarged end 10 adapted to be received in the enlarged end 7 of the stationary tube, and this enlarged end 10 is 70 provided with external threads 11 with which engages an internally threaded adjusting collar 12 upon which is engaged an externally knurled adjusting nut or ring 13, the same being formed with an internal annular flange 14 for engagement with an external flange 15 formed on the stationary tube 5 so that on the adjustment of the slide tube 9 the nut or ring 13 will not separate or ride off of the stationary tube. 75 Adapted to be fitted within the enlarged end 10 of the slide tube 9 is the mouth piece B. Mounted in the shoulder 16 formed by the enlarged end 10 of the slide tube 9 is a guide pin 17, the same working through a 80 correspondingly shaped aperture or hole 18 formed in the shoulder 19 provided by the enlarged end 7 of the stationary tube 5, and this guide pin 17 serves to prevent the turning of the mouth piece on the adjustment of 85 the slide tube for the tuning of the clarinet. Upon adjustment of the nut or ring 13 the slide tube 9 can be moved so as to enable the clarinet to be properly tuned without the possibility of the formation of air gaps 90 which ordinarily occur when drawing out the barrel joints of this instrument.

From the foregoing description, taken in connection with the accompanying drawing, the construction and manner of operation of 100 the device will be clearly understood, and therefore a more extended explanation has been omitted.

What is claimed is:—

A tuning joint comprising a barrel, a lining within said barrel, a slide tube within the lining having a socketed end receiving the mouth piece of a musical instrument, ex-

ternal threads formed on the socketed end of the slide tube, an adjusting collar engaging said threads, a turning nut on the collar having swiveled connection with the lining, 5 and a guide pin carried by the slide tube and engageable in the lining to prevent rotation of said slide tube.

In testimony whereof I affix my signature in presence of two witnesses.

WILLIAM F. REYNOLDS.
